MOVING TARGET

James Hanson, Hudson, Mass.

Application December 4, 1945, Serial No. 632,745

4 Claims. (Cl. 273—105.2)

1

This invention relates to improvements in moving targets for target practice in shooting galleries mounted on an endless conveyor belt or chain which travels over a more or less horizontal stretch. It has for its principal object to provide a target of the type above mentioned which imitates the movement of a fox, and which carries a bull's eye operating directly by simple mechanical means, an acoustical and optical signal means when hit by a bullet. This construction is simple, sturdy and compact, so that it cannot get out of order even if subjected to very rough handling; the whole target operation requires only the services of one man who may attend the practicing customers and has only to start or stop the motor. No further service or inspection is required as the hitting of the target is announced automatically.

A further object of the invention consists in means for keeping the bull's eye clearly marked and clearly distinguishable by means of paint in spite of hits sustained which have a tendency to crack and to remove any coating of paint which may have been applied.

Further objects will be apparent from the following specification.

The invention is described with reference to one modification illustrated in the drawing. It is, however, to be understood that the fact that merely one modification is described is not to be regarded as limitative. The invention is described in such terms that other embodiments than such shown are foreshadowed and suggested to the expert skilled in the art and these embodiments, therefore, do not form a departure from but constitute part of the invention.

In the accompanying drawings:

Figure 1 is a perspective view of the moving target and the various means employed.

Figure 2 is a perspective view of the animal figure forming the target (the silhouette of a fox being selected) carrying the optical and acoustical signalling means and the mechanism for operating the same.

Figure 3 is a perspective view similar to that of Figure 2 showing the parts of the mechanism in their position after a hit of the bull's eye.

Figures 4, 5 and 6 are elevational side views of details of the signal releasing mechanism.

Figure 7 is an elevational view of the painting mechanism.

As shown in Figure 1 the target consists of the figure of an animal (a fox being shown) cut out of a sheet iron plate of appropriate thickness. This figure consists mainly of two parts. The

body 1 carries the bull's eye, generally indicated by 3, and the acoustical signalling device and the entire mechanism for operating the signals when the bull's eye is hit by a bullet. The tail 2 is pivoted to the body 1 by means of a pivot bolt 4 and forms the optical signal indicating a hit; for said tail is carried in a horizontal or elevated position when the target starts, but is dropped whenever the bull's eye is hit.

The bull's eye, generally indicated by the reference numeral 3, consists of a target disc 5 mounted on a sleeve 6 which is internally threaded. The sleeve may have the shape of a square or hexagonal nut as shown in Figures 4 and 5 in order to be able to screw it on firmly to a stem 7, provided with screw threads at its end. This stem is carried by a guide sleeve 8, which carries at its end a circular screw threaded head 9, screwed into a suitable opening 10 of the body 1 of the target figure and firmly secured thereto, if necessary, by nuts on screw threaded discs 11. The guide sleeve 8 projects rearwardly and is partially cut so that it extends only around $\frac{3}{4}$ of the circumference. Through it the stem 7 of the bull's eye passes. The guide sleeve is of sufficient length to hold the stem firmly without permitting jamming or edging even if the target disc should be hit eccentrically.

Between the sleeve 6 and the body 1 of the target or between said sleeve and one of the nuts 11 a strong compression spring 12 is arranged.

On the stem 7 lugs 14 are secured which are so arranged that they project upwardly through the cut portion of the guide sleeve 8. These lugs carry a pivot 15 around which a dog 16 may rock. The dog has a cut or recessed portion 17 against which a compression spring 18 is applied which opposes a counterclockwise movement of the dog, as shown in Figure 6.

The upper portion of the dog has a hook-like projection 20 bordered by an inclined face 21. It cooperates with a pin 22 which is mounted on a projection 23 of the tail 2.

The acoustic signal consists of a bell 24 which is sounded by a striking lever 25 capable of moving around a pivot 26 which may be mounted on the top of the bell. The lever 25 may simply consist of a wire, as shown, which is passed through a slot or hole 28 in the stem 7 and may be secured by a spline 30.

The movement of the target is obtained by means of a pair of conveyor belts or chains 35, 36 (Figure 1) to which the body 1 of the figure carrying the target is fixed by means of transversal supporting frames 37 screwed to the said

body 1. The supporting frames in their turn are fixed to the links of the chains 35, 36.

The chains run over pairs of sprocket wheels 40, 41, 42, 43, each pair being carried by a shaft 45, 44, respectively. One of said shafts 45 is provided with a pulley 46 which is driven by means of a speed reduction gear 47 from a small motor 48. The shafts of the sprocket wheels are journalled in a frame structure 31, 32.

Between the sprocket wheel pairs 40, 41, 42, 43 further pairs of sprocket wheels 50, 51, 52, 53 are arranged which are eccentrically mounted on their shafts 54, 55. The upper portions of the chains pass over these sprocket wheels and will, therefore, alternately be raised and lowered. The target figure drawn along by the chains will, therefore, be raised and lowered with the chains in rapid succession and will perform a movement which is very similar to the jumping action of an animal as first the fore part and then the aft portion is rapidly raised and lowered. The number of jumps the target figure will perform while passing over the eccentric sprockets will be determined by the number of pairs of eccentric sprocket wheels. It is preferable to arrange the eccentric sprocket wheels in such a way that adjacent pairs adopt different positions of their centers with respect to the centers of the shafts upon which they are mounted so that the tension of the chains does not vary very much during the rotation of the eccentric wheels.

In order to be able to distinguish the bull's eye from the background it is preferable to mark it vividly with some distinctive color. It is under ordinary circumstances, as a rule, not of advantage to paint the bull's eye of a target as the paint under the impact of bullet hits and on account of the rise of the temperature during such hits disappears, drops or scales off within a very short time. This time is so short that it would not pay to interrupt the operation as many times as is necessary to keep the bull's eye in good condition.

According to the invention a bull's eye painting arrangement is provided which may be used to apply paint as often as necessary without interrupting the operation and without compelling the attendant to approach the target.

Near the sprocket wheels at the end where the animal figure is taken around said wheel a curved arm 60 is secured to the framework 34 which may be turned around a pivot 61 and carries a brush 62 which dips into a container 63 with paint. The arm may be under the tension of a spring 64. The curved end of the arm is provided with an eye 65 to which a cord, rope or chain 66 is attached which runs to the stand of the attendant. The attendant may pull the cord when the fox figure reaches the end of its visible run and in this case the brush 62 is brought into the path of the disc 5 of the bull's eye 3. Fresh paint will be applied to the said disc so that the latter is always kept brilliantly painted. The paint may be so selected that it dries fast, but the very fact that the paint is wet will tend to preserve it for some time as a hit will in this case only leave its trace but will not crack and remove the paint.

The operation of the device will be clear from the foregoing description. At the start of the run of the fox the parts are in the position shown in Figure 2 with the tail held in a horizontal position by virtue of the pin 22 engaging the hook 20 of dog 16. When the attendant operates a switch controlling the driving motor the lat-

ter will start to run and to move the sprocket wheels. The conveying chains will be drawn along and with it the figure of the fox will be drawn along. The fox will pass the eccentric sprocket wheels and will seem to jump over them with the bull's eye going up and down in addition to being drawn in the forward direction.

If a bullet hits the bull's eye 3, the disc 5 will be pushed back and the spring will be compressed. Therefore, the stem 7 moves rearwardly, the hook 20 of dog 16 which originally was engaging and holding pin 22 of tail 2 is moved backwards (to the left in Figure 4) and the hook loses its grip on the pin by virtue of its lateral displacement. Therefore, the tail 2 drops, thus giving a clear optical signal indicating that the bull's eye was hit. Simultaneously the wire 25 is pressed in the same direction in which the stem 7 moves and the striker is moved towards the bell 24 and sounds it so as to give a clear bell signal.

The tail is now hanging down as shown in Figure 3. In order to be still visible it may be held by a stop pin 19 on its end.

The fox now comes to the end of the frame structure and starts to pass the wheel. If the paint on the bull's eye is not clearly seen the attendant at any moment preceding the downward movement of the fox over the sprocket wheel at the end pulls the cord 63. The brush 62 is thereby raised with the position shown in Figure 7 in dotted lines and the disc will be painted during its passage.

When the fox has turned around the weight of the tail 2 (which may be supplemented, if necessary, by some lead weights 69 held by bolt 19) will tend to align the tail again with the body. The pin 22 then meets the inclined surface 21 and presses it back against the pressure of spring 18 which will be overcome by the weight of the tail. Therefore, pin 22 again slips under hook 20 and is held thereby so that the mechanism on the fox figure is again in the position shown in Figure 2 when it starts its target run.

It will thus be seen that all operations which are necessary to run the target are such that they may be performed by one attendant standing on a remote point where he can attend to the customers, charge and hand out rifles and perform other duties.

It will be obvious that many changes may be made in the details of the construction without departing from the invention.

I claim:

1. A moving target for shooting galleries comprising a pair of parallel endless conveyor chains, sprocket wheels for supporting and driving the conveyor chains of the pair at equal speed, a target figure arranged between and carried by the chains, a disc forming a bull's eye, transversely movable on said target figure, a movable signal member pivoted to said target figure, a spring pressed stem associated with said disc, a movable dog provided with a hook carried by said stem, a holding member engaging said dog when in its original position, on said movable signal member during travel of the target figure on the upper stretch of the conveyor, said member being moved out of engagement and released by a transverse movement of the stem and means on said dog for moving the holding member into re-engagement with it under the influence of gravity during travel of the target figure on the lower stretch of the conveyor chains.

2. A moving target for shooting galleries as specified in claim 1, wherein said dog is pivotally

fixed on said stem, a spring arranged at right angle to the axis of the stem holding the dog in its position and in inclined surface arranged above the hook surface, for moving the dog into reengagement with the holding member upon movement of the signal member in a direction opposite to its original movement under the influence of gravity during the travel of the target figure along the lower stretch of the conveyor chains.

3. A moving target for shooting galleries comprising endless conveyors, wheels for carrying the same, a frame for mounting the conveyors, a target figure mounted upon said conveyors, a disc forming a bull's eye on said target figure, a brush and a brush support, the latter pivotally mounted on said frame, means for moving said brush carrier from a remote place, and a paint container, said brush being moved from said container into the path of the passing disc upon operation of the aforesaid means.

4. A moving target for shooting galleries comprising a pair of endless parallel conveyors with an upper and a lower section, means for driving and supporting the same, a target figure, arranged between them and fixedly carried by the said pair of conveyors, a bull's eye carried by and trans-

versely movable on said target figure, a signal member pivoted to said target figure for indicating hits on the same, movable means connected with said bull's eye including a movable catch adapted to hold the signal member and to release the same upon transverse movement on the upper conveyor stretch and to be moved into engagement with said signal member by the pressure of said member on the said catch under the influence of gravity during the travelling of the target figure on the lower section of the conveyor.
